UNITED STATES PATENT OFFICE

2,577,954

NAIL SET

Louis J. Di Pietro, Waterbury, Conn.

Application May 6, 1948, Serial No. 25,393

3 Claims. (Cl. 145—46)

1

This invention relates to tools for setting nails, and more particularly to a nail set having a laterally disposed handle.

One object of this invention is to provide a device of the above nature which includes improved means for holding the tool in alignment with a nail being set, whereby the setting operation will be facilitated.

A further object is to provide a device of the above nature which will be simple in construction, inexpensive to manufacture, easy to manipulate, compact, ornamental in appearance, and very efficient and durable in use.

With these and other objects in view, there have been illustrated on the accompanying drawings two forms in which the invention may conveniently be embodied in practice.

In the drawings,

Fig. 1 is a side view of the improved nail set as it would appear during use.

Fig. 2 is an end view of an adaptation of the tool, wherein the bit portion is modified to serve as a center punch.

Referring now to the drawing, in which like reference characters denote corresponding parts throughout the several views, the numeral 10 indicates the nail set generally, which comprises a tapered bit portion 11, and an integral laterally-extending shank 12 which is inclined downwardly from the upper part of the bit portion 11.

In order to provide a surface suitable to receive the impact of a hammer H, the upper surface of the shank 12 is formed with an integral beveled anvil boss 13 in alignment with the bit portion 11.

The outer end of the shank 12 is enlarged upwardly to form a handle 14 which is preferably knurled and recessed upon its side surfaces so that the tool may be firmly gripped by the carpenter, or other person using said tool.

The outer end of the shank 12 is also provided with a flat base surface 15 which is disposed in substantially the same plane as the end of the bit portion 11, in order that the nail set 10 may be firmly supported upon a board B in proper position to set a nail N in said board.

Operation

In operation, the nail N will, of course, be driven down by the hammer H until its head is nearly flush with the surface of the board B, whereupon the nail set 10 will be applied to the nail N, and manually held by means of the handle 14. The anvil boss 13 will be struck by the hammer H in order to set the nail N as shown in Fig. 1. Inasmuch as the flat base surface 15 of the shank 12 is disposed in approximately the same plane as the end of the bit portion 11, the nail set 10 will have a stable support upon the board B.

Further, the nail set 10 will not be likely to overturn when receiving an oblique blow from the hammer H, and even if it does overturn, no injury

2

can be inflicted upon the user's hand by the hammer H. The offset relation of the handle 14 will also permit the nail set 10 to be held without obscuring the work.

5 One advantage of the improved nail set is that it will enable the carpenter to set nails at a very rapid rate without fatigue.

Modified form

10 The tool described above may be modified to provide a center punch 16, as shown in Fig. 2, which is similar to the nail set 10 except that the tapered bit portion 17 has a point 18 at its lower end.

15 Thus, the center punch 16 will have all the advantages of the nail set 10 in that it may be easily and firmly held by the user without likelihood of injury to his hands.

While there have been disclosed in this specification two forms in which the invention may be embodied, it is to be understood that these forms are shown for the purpose of illustration only, and that the invention is not to be limited to the specific disclosures, but may be modified 20 and embodied in various other forms without departing from its spirit. In short, the invention includes all the modifications and embodiments coming within the scope of the following claims.

Having thus fully described the invention, what 25 is claimed as new, and for which it is desired to secure Letters Patent, is:

1. In a tool, an elongated shank having an integral vertical bit portion, said shank being inclined at an acute angle away from said bit, 30 an elongated, relatively wide, heavy, flat-surfaced bottom base on said shank at the other end thereof, said bit portion having a lower extremity disposed in the plane of said base surface, whereby said tool will be stable upon a flat supporting surface and said shank will be raised from said base bottom to said bit portion.

2. The invention as defined in claim 1, in which said shank is provided with an elongated handle disposed adjacent said base surface.

3. The invention as defined in claim 1, in which the extremity of said bit portion is circular, whereby said tool is adapted for setting nails.

LOUIS J. DI PIETRO.
